LUBRICATED HINGE

Filed June 2, 1932

FIG. 1.

FIG. 2.

FIG. 3.

Inventor

FIG. 4. DAVID A. BRAWLEY

By Milo B. Stevens and Co.

Attorneys

UNITED STATES PATENT OFFICE

DAVID A. BRAWLEY, OF FLINT, MICHIGAN

LUBRICATED HINGE

Application filed June 2, 1932. Serial No. 615,004.

My invention relates to lubricated hinges. An object of my invention is to provide lubricated hinges particularly fitted for use on automobile doors.

5 A further object is to provide a hinge, the pintle of which contains an oil cup for lubricating the same and preventing wear even when the pintle has been tightly fitted.

A still further object is to provide a hinge 10 which will not become loose with age, will prevent squeaks and rattles in the door, and which will allow easy removal of the door when it is so desired.

Further objects and advantages will be apparent from the following description which, 15 taken in connection with the accompanying drawing, in which like numerals refer to like parts throughout the same,

In the drawing:

20 Fig. 1 is a side view of my device installed on an automobile door;

Fig. 2 is a vertical longitudinal section through the hinge and pintle, as on line 2-2, Figure 3.

Fig. 3 is a section on the line 3-3 of Fig. 2, and

Fig. 4 is a perspective view of the hinge pintle.

The numeral 5 designates an automobile door, and 6 and 7 designate the two sections of a hinge therefor. The head portion of the pintle is designated as 8, and the shank as 9, the said head portion having a cavity 10 in its top for receiving a self-closing oil cup 11 of any suitable construction. Centrally located in the bottom of the cavity 10 is a well 12 extending down into the shank portion 9 of the pintle. In the upper portion of the shank 9 is centrally disposed a horizontal passage 13, the said passage piercing the well 12 at a point above its bottom. Extending downwardly from the outer openings of the horizontal passage 13 are formed slots 14, the said slots ending at a point adjacent to the bottom of the shank 9, thus preventing oil from dripping out the bottom of the hinge.

50 In operation, oil from the cup 11 flows down into the well 12, out through the ends of the passage 13 and down the slots 14,

where it is spread over the surface of the pintle shank 9 by the working of the hinge. Even after the oil level in the well 12 has fallen below the point of intersection by the passage 13, the jolts and jars of the car will 55 throw same up into the passage 13, thus continuing the lubrication of the pintle until practically all of the oil in the well has been exhausted. Furthermore, my device will continue to permit the tight installation of pintles as is now the practice and, by preventing pintle wear, will do away with the noise common to hinges and doors during the operation of the car. It is to be understood that my invention as above shown and described 60 is to be taken as a preferred embodiment of same, and that changes in shape, size, and arrangement of parts may be made without departing from the spirit of the invention or of the scope of the subjoined claims. 70

Having thus described my invention, what I wish to claim by Letters Patent is:

1. In a hinge, a pintle having head and shank portions, an oil cup receiving cavity in the top portion of said head, a well in the 75 bottom of the cavity, a horizontal passage through the upper portion of the shank portion, said passage bisecting the well at a point above its bottom, and slots on the shank portion extending downwardly from the ends of the said horizontal passage, said slots ending at a point adjacent to the bottom of the shank.

2. In a hinge, a pintle having head and shank portions, an oil cup receiving cavity 85 in the top portion of said head, a well in the bottom of the cavity, a horizontal passage through the shank portion adjacent the upper end of same, said horizontal passage bisecting the well at a point above its bottom, 90 and slots on the shank portion extending downwardly from the ends of the horizontal passage.

In testimony whereof I affix my signature. DAVID A. BRAWLEY. 95
